Primary Examiner — Jennifer Rivard*Assistant Examiner* — Jennylo M Binas(74) *Attorney, Agent, or Firm* — John H. Choi & Associates(57) **CLAIM**

The ornamental design for a cleaning device attachment, as shown and described.

DESCRIPTION

FIG. 1 is a front perspective view of a cleaning device attachment showing my new design;

FIG. 2 is a front plan view of the cleaning device attachment of FIG. 1;

FIG. 3 is a rear plan view of the cleaning device attachment of FIG. 1;

FIG. 4 is a right side view of the cleaning device attachment of FIG. 1;

FIG. 5 is a left side view of the cleaning device attachment of FIG. 1;

FIG. 6 is a top plan view of the cleaning device attachment of FIG. 1; and,

FIG. 7 is a bottom plan view of the cleaning device attachment of FIG. 1.

The features shown in broken lines are for the purpose of illustrating portions of the cleaning device attachment that form no part of the claimed design.

1 Claim, 7 Drawing Sheets(56)
